ATTORNEY

UNITED STATES PATENT OFFICE.

HUGH M. ROCKWELL, OF BRISTOL, CONNECTICUT, ASSIGNOR, BY MESNE ASSIGNMENTS, TO THE MARLIN FIREARMS CORPORATION, OF NEW HAVEN, CONNECTICUT, A CORPORATION OF DELAWARE.

BELT-LOADING MACHINE.

Application filed October 14, 1918, Serial No. 257,947. Renewed November 21, 1921. Serial No. 516,900.

To all whom it may concern:

Be it known that I, HUGH M. ROCKWELL, a citizen of the United States, residing in the city of Bristol, county of Hartford, and 5 State of Connecticut, have invented a new and useful Improvement in a Belt-Loading Machine, of which the following specification is such a clear and exact description as to enable one skilled in the art to which it 10 appertains to make and use the same.

This invention relates to a device for assembling cartridges and links to form a belt of the disintegrating type.

Devices of this character comprise a bed 15 having means for positioning a plurality of cartridges and links in assembling relation, means for preventing movement of the links and a pusher bar for simultaneously forcing the cartridges into the links and means for 20 operating the pusher bar. It is the object of this invention to improve generally upon these devices and to provide a machine which is highly efficient in operation.

An additional object is to provide means 25 whereby the path of travel of the pusher bar may be changed without varying the length of the path. This object is attained by providing an adjustable connection between the pusher bar and the operating means. By 30 adjusting this connection the device may be regulated to thrust the cartridges the exact desired distance into the links without utilizing positive stops.

A further feature of the invention resides 35 in the mode of connecting the operating means to the bed. Brackets, having vertical slots, are arranged at either end of the bed and an operating bail is provided with rollers on its ends to engage in said slots.

40 The ends of the pusher bar are journalled in the ends of the bail and horizontal guides for the pusher bar are arranged on the bed. This arrangement produces a sturdy structure which allows applying the necessary 45 pressure to the operating means without danger of affecting the efficient operation of the device.

Other objects and features of the invention will be apparent from the following 50 specification and accompanying claims.

Referring now to the drawings:

Fig. 1 is a perspective view of my device; 55 Fig. 2 is a side elevation thereof;

Fig. 3 is a detail of a part of the operating lever.

The device comprises a bed 1 having grooves 2 on the upper surface, one side of said bed having stops or lugs 3 forming the U shaped spaces 4. At either end of the bed, spaced therefrom and near the rear edge 60 thereof, are the brackets 5 provided with the slots 6, the lower ends of which are open. Carried by the ends of the bed are the guide plates 7 in which are provided the slots 8, closed at each end, but which exceed in 65 length the throw of the pusher bar to be later described.

The operating lever 9 is bail shaped and has forked or divided ends comprising the two arms 10 and 11. Extending through the slots 6 and joining the arms 10 and 11 are the pins 12 on which are mounted the rollers 13. Set in the arms 10 are the eccentric bushings 14 which are held against rotation by the set screw 15. Journalled in these 75 bushings are the ends of the pusher bar 16.

In using this device the links L are placed 80 in the grooves 2 as shown in Fig. 1 and then the cartridges C are also laid in the grooves but to the rear of the links and inspected. I 85 have shown only a few of the links and cartridges in place but in practice the whole bed is filled. Before this is done the operating lever has been moved so that the pusher bar is in its rearmost position. The operating lever is then thrown forward until it 90 has assumed a horizontal position. The lever pivots around the ends of the pusher bar and the rollers 13 move down and up in the slots 6 causing the pusher bar which is held against vertical movement by the sides of the slots 8 to be moved forward. The forward movement of the pusher bar forces the cartridges into the links which are prevented 95 from moving forward by virtue of the stops 3. When the lever has assumed a horizontal position, the pusher bar has been advanced the full extent of its throw and has forced the cartridges into place in the links forming a belt of limited length. The operating lever 100 is then returned to its initial position, the belt and cartridges picked up and moved along and the end link is placed in the last groove after which the operation is repeated.

After considerable usage, the thickness of 105 the stops 3 is decreased and the cartridges

would not be forced far enough into the links. Adjustment of the eccentric bushing 14 is then made to throw the pusher bar forward enough to compensate for this wear.

5 Thus it is seen that I have provided a simple and efficient belt loading machine which combines with simplicity of construction and operation, a high degree of efficiency.

10 It is obvious that various modifications may be made in the structure of this device without in any way departing from the spirit of the invention as defined in the accompanying claims.

15 I claim as my invention:

1. A device of the character described comprising a bed, means thereon to position in assembling relation to each other a plurality of receptacles and articles to be introduced into said receptacles, a pair of guideways on said bed at an angle to each other, and means for forcing said articles into said receptacles, said means having portions arranged in said guideways.

20 2. A device of the character described comprising a bed, means thereon to position in assembling relation to each other a plurality of receptacles and articles to be introduced into said receptacles, a pair of

25 guideways on said bed at an angle to each other, means for forcing said articles into said receptacles, said means having portions arranged in said guideways, and means for adjusting said forcing means.

30 3. In a machine for loading cartridges into a disintegrating link belt, means to position in assembling relation a plurality of cartridges and links, pusher means to force the cartridges into the belt, operating means for said pusher means and connecting means between said pusher means and said operating means including an eccentric bushing.

35 4. In a loading machine, a bed, brackets having vertical slots therein at either end

40 of the bed, guides carried by the bed, a bail shaped lever having forked ends, eccentric bushings carried by the inner arms of said forked ends, rollers carried by each set of said arms and extending through said

45 slots, and a pusher bar extending through

said guides having its ends journalled in said eccentric bushings.

5 In a loading machine, a plate, a pusher bar reciprocatively mounted on said plate, an operating lever for said pusher bar carried by said plate, and an adjustable eccentric bushing mounted in said operating lever, said pusher bar having a portion received in said bushing.

6 In a loading machine, a bed, brackets having vertical slots therein at either end of said bed, a reciprocating pusher bar, an operating lever pivotally connected to said pusher bar, and means carried by said operating lever adapted to reciprocate in said slots.

7 In a loading machine a bed, brackets having vertical slots therein at either end of said bed, a reciprocating pusher bar, guiding means therefor, an operating lever pivotally connected to said pusher bar and means carried by said operating lever adapted to reciprocate in said slots.

8 In a loading machine, a bed, brackets having vertical slots therein at either end of said bed, a reciprocating pusher bar, guiding means therefor, an operating lever provided with adjustable bushings in which are journalled the ends of the pusher bar and rollers carried by the lever to engage in said slots.

9 A cartridge-linking machine comprising a bed, means thereon to position in assembling relation to each other a plurality of cartridges and links, and means consisting of a slidable bar and a connected lever for forcing the cartridges into the links, the connection between said bar and lever including means for varying the position of said bar relative to said lever.

10 In a loading machine, a bed, brackets at either end of said bed having slots therein, an operating lever having its ends reciprocatively mounted in said slots, eccentric bushings adjustably mounted in said lever, guides carried by the bed, and a pusher bar extending through said guides having its ends journalled in said eccentric bushings.

HUGH M. ROCKWELL.
